[57] CLAIM

The ornamental design for an industrial window, as shown and described.

DESCRIPTION

FIG. 1 is a top plan view of the first embodiment of my design for an industrial window.

FIG. 2 is a left side elevational view thereof.

FIG. 3 is a front elevational view thereof.

FIG. 4 is a right side elevational view thereof.

FIG. 5 is a rear elevational view of this first embodiment.

FIG. 6 is a bottom plan view thereof.

FIG. 7 is a top plan view of the second embodiment of my design.

FIG. 8 is a left elevational view thereof.

FIG. 9 is a front elevational view thereof.

FIG. 10 is a right side elevational view thereof.

FIG. 11 is a rear elevational view of this second embodiment.

FIG. 12 is a bottom plan view thereof.
